CABLE CLAMPING DEVICE FOR
FEEDER TAPSElmo F. Huston, Mansfield, Ohio, assignor to The
Ohio Brass Company, Mansfield, Ohio, a cor-
poration of New Jersey

Application June 1, 1950, Serial No. 165,435

2 Claims. (Cl. 339—250)

1

This invention relates generally to feeder taps and is particularly concerned with a feeder tap having means which spirals a cable end into a sector shape and clamps it in place. It also relates particularly to a feeder tap which is provided with combined means for venting the casing and adjusting the parts thereof to accommodate manufacturing variations in dimensions.

In prior feeder taps the cable has been attached to one of the fuse-engaging plugs, as by a cap screw and clamp such as is shown in Chandler Patent No. 1,822,883, or other securing means. While these securing means have been used commercially, they have not been entirely satisfactory and, accordingly, one object of the present invention is to provide a new cable securing means which avoids the disadvantages of the securing means and possesses new advantages.

Prior feeder taps have been provided with casings which were to engage at one end with an insulating cap and vents were provided in the cap to relieve pressure within the casing. Manufacturing tolerances often caused imperfect positioning of the parts within the casing or left a space between the insulating cap which, under certain conditions of use, could become filled with wet mud and might then deliver a charge of electricity to an operator whose hand might come into contact with the mud. Accordingly, it is another object of this invention to provide an insulating cap which will not only accommodate manufacturing tolerances and insure predetermined relative positioning of the parts of the tap, but will also insure against an operator receiving a shock when in contact with the guard.

The present invention will be better understood by those skilled in the art from the following specification read in connection with the accompanying drawings, in which:

Fig. 1 is a longitudinal, sectional view of one form of feeder tap embodying the present invention;

Fig. 2 is an end elevational view of the insulating guard at the power-receiving end of the tap;

Fig. 3 is a cross-sectional view taken on line 3—3 of Fig. 2;

Fig. 4 is a detailed sectional view of the cable-engaging plug of the tap of Fig. 1;

Fig. 5 is an end elevational view of the plug at the power-receiving end of the tap;

Fig. 6 is a view, partly in elevation, and partly in section, taken on line 6—6 of Fig. 5;

Fig. 7 is a side elevational view of the fuse of Fig. 1;

2

Fig. 8 is a transverse, sectional view taken on line 8—8 of Fig. 4; and

Fig. 9 is a fragmentary, cross-sectional view taken substantially on line 8—8 of Fig. 4 but showing the wires of a power-delivering cable clamped in the plug of Fig. 4.

In the drawings, the illustrated feeder tap comprises an insulating casing consisting of a tube 1 and a lining 2. While various materials may be used to form these parts, it has been found that the tube 1 may consist of phenolic canvas, i. e., canvas impregnated with a phenol condensation product such as Bakelite or any other suitable plastic material. The lining 2 of this tube is preferably composed of asbestos. As will be noted, the tube part 1 of the casing is threaded at each end and the lining 2 is positioned between these threaded portions. An insulating cap 3 is screw-threaded into the power-delivering end of the casing and a sleeve 4 threaded on its inner and outer surfaces is screwed into the other or power-receiving end of the casing. The cap 3 and sleeve 4 may abut against the opposite ends of lining 2.

An electrically conducting plug 5 is screw-threaded into sleeve 4 and carries at its outer end a plate 6 to which is vulcanized, or otherwise suitably secured, a guard 7 composed of insulating material. The guard 7 is attached to plug 5 as by screws 8 extending through holes 9. It will be noted, by reference to Fig. 1, that even when the plug 5 is screwed into sleeve 4 as far as is permitted by parts within the casing the plate 6 will be spaced from the end of tube 1. The guard 7 has a recess defined by cylindrical side wall 10 and end wall 11 and each of these walls is spaced apart from the adjacent opposed surfaces of tube 1 for purposes presently to appear.

The guard is provided with vent holes 12 which are aligned with similar holes 13 extending longitudinally through plug 5 and opening into the interior of the casing. Gas pressure created within the casing may escape through holes 12 and 13. The main advantage of the spacing between the guard and casing end is that manufacturing tolerances can be accommodated by variation in the dimensions of these spaces as will be understood by those skilled in the art.

The plug 5 has an axial opening screw-threaded at the outer end to receive a conductor 15 which may be connected to a source of power, for example, by being hooked over a power line. At its inner end this axial opening is threaded to receive a threaded stud 20 attached to or extending through the end cap 21 of fuse casing 22.

The other end of the fuse casing is provided with a similar cap 21' and threaded stud 20' and the latter stud is threaded into the axial opening in plug 25. The plugs 5 and 25 have tubular end portions facing each other and these portions are slit lengthwise to provide resilient fingers 26 within which the end caps 21 and 21' of fuse casing 22 may be received and by which they may be frictionally gripped to insure good electrical contact therewith in addition to the contact afforded by the threaded studs 20 and 20'. The inner ends of the studs are connected to the ends of the fuse link 20".

Plug 25 abuts at its outer end with the insulating cap 3. This plug is provided with a longitudinally extending recess which includes a generally cylindrical portion 30 and a parallel sided portion 31 extending to the periphery of the plug. The cylindrical portion 30 is preferably transversely corrugated as indicated at 32 to present a roughened surface against a cable end which is to be clamped in the recess. A lever or clamp 33 is disposed in portion 31 of the recess and is rotatable on a pin 34. This lever has parallel sides disposed closely adjacent to the sides of recess 31 and has a cam-shaped inner edge surface 35 opposed to the corrugated portion of recess 30. When a cable is to be connected operatively with plug 25 the lever 33 is rotated about pin 34 to the dotted line position to move it away from the corrugated surface 35. Then the cable end is placed in recess 30 and the lever is rotated to the full line position shown in Fig. 4 with resultant clamping, spreading and shifting of the wires of the cable so that they will move into and substantially fill the sector-shaped part 36 of the cylindrical recess which remains after the lever 33 has been moved into its cable clamping position in Fig. 4. The casing 1 holds the cam lever 33 in clamping position and thus prevents accidental release of the cable.

It will be understood from the foregoing description that the cam clamping device here illustrated possesses many advantages. It affords a grip with the cable which extends over a large surface area due to the spreading out of the strands of the cable into a sector shape with the cam engaging the inner surface of the sector and impressing the strands against the outer surface of the sector. This clamping device may be operated without the use of tools and the cable cannot be loosened while the feeder tap is in assembled position. It will also be noted that the assembled parts of this invention afford increased venting capacity and part of the space provided for accommodation of manufacturing tolerances may also serve as part of the venting system. The spacing between plate 6 and the adjacent end of the casing 1 may serve to relieve internal pressure in the casing and also to insure predetermined positioning of the parts of the device in spite of variation in dimensions due to manufacturing tolerances. Another advantage in the present construction is the provision of threaded studs which may be connected to the end caps of the fuse casing 22 which materially supplement the electrical conducting action of the fingers 26.

The corrugation 32 may, in some cases, be omitted, especially when the cable is composed

of relatively small wires, some of which are apt to be injured or even severed by the corrugation.

Having thus described the present invention so that others skilled in the art may be able to understand and practice the same, I state that what I desire to secure by Letters Patent is defined in what is claimed.

What is claimed is:

1. A cable clamping device for use in a feeder tap comprising a fuse-receiving plug having a body portion provided with a longitudinally extending, generally cylindrical, cable-receiving recess of greater cross-sectional area than the cable to be clamped therein, and a cam lever pivoted in said body portion, said lever being of less width than the diameter of said recess, having a cam-shaped, transversely convex inner edge surface defining with the walls of said cable-receiving recess a space of crescent-shaped cross-section of slightly less cross-sectional area than that of the cable to be clamped therein, said cam lever being movable to bring its cam-shaped convex edge surface into the cable-receiving recess and to spread the end of the cable in said recess into substantially all parts of said crescent-shaped space and to clamp the cable in place therein.
2. A cable clamping device for use in a feeder tap comprising a fuse-receiving plug having a body provided with a generally cylindrical recess extending at a small angle to the longitudinal centerline of the plug and having a cross-sectional area considerably larger than that of the cable to be clamped therein, and a parallel-sided recess extending from said cylindrical recess to the periphery of the plug, a cam lever pivotally mounted in said parallel-sided recess and having parallel sides disposed closely adjacent to the sides of said recess and having a cam-shaped, transversely convex inner edge surface, said lever being pivotally movable into a position where its cam-shaped convex surface extends approximately to the axis of the cylindrical recess and defines with the inner surface of the latter recess a crescent-shaped space having a cross-sectional area slightly less than that of the cable to be clamped therein, said cam lever serving, when the cam portion thereof is brought into said cylindrical recess, to spread and shift the wires of the cable into, and to fill, substantially all parts of the sector-shaped recess and to clamp the cable in place therein.

ELMO F. HUSTON.
